West Newton, Mass. 02165

Filed Nov. 12, 1965, Ser. No. 88,064

Term of patent 14 years

(Cl. D86—1)

Fig. 3.

Fig. 2.

Fig. 1.

The hair sprayer as seen from the front appears as a plain tapered body with details as indicated in FIGS. 1, 2 and 3, having rounded shoulders and a pedestal at the base like that shown for the rear in FIG. 2.

I claim:

The ornamental design for a hair sprayer, as shown and described.
